By his Attorney
Inventor
William Szlanyi
Frank Ledermann

UNITED STATES PATENT OFFICE.

WILLIAM SZLÁNYI, OF NEW YORK, N. Y., ASSIGNOR OF ONE-FOURTH TO MALVINA SCHMIDECK AND ONE-HALF TO HENRY DOHRMANN, BOTH OF NEW YORK, N. Y.

PERMANENT-HAIR-WAVING DEVICE.

1,334,719.

Specification of Letters Patent. Patented Mar. 23, 1920.

Application filed November 7, 1919. Serial No. 336,330.

To all whom it may concern:

Be it known that I, WILLIAM SZLÁNYI, a citizen of the United States, residing at New York, in the county of New York and State of New York, have invented certain new and useful Improvements in Permanent-Hair-Waving Devices, of which the following is a specification.

This invention relates to improvements in permanent hair waving devices, and has for its main object the provision of such a device which will permanently and naturally wave the hair in imitation of natural waves.

Another object of the invention is to provide a central rod upon which the hair is wound from the outer ends, in the fashion of cloth upon a roll, all the way up to the head of the person, whereby, when the device is removed, the hair will possess waves similar to natural hair waves, for the curves will be of relatively greater diameter at the head than at the end of the hairs, decreasing proportionately with the distance from the head. In the old method of hair waving, the central rod is held at the head, and the hair is wound upon it from the head end to the outer end; from this it is apparent that this method produces waves or curves of greater diameter at the outer end than at the head, which is unnatural.

Another object of my invention is the provision of a compact heater and casing, by means of which the hair, after being wound upon the central rod, is warmed and thus the waves are made permanent.

Another object is the provision of such a casing which opens into two longitudinal halves and, when closed, permits the hair to pass through the space between the halves; for, my method allows the hair to leave the casing in the form of a pad, as seen in Fig. 1 of the drawings, contrary to the old method by which the hair leaves the end of a closed tube. Thus, while the hair is being heated, and the person is abiding this operation, the tube is held end-wise upon the head of the person. My method, however, permits the tube to be held side-wise against the head, which is both a more comfortable position for the person and a better position for the permanent waving of the hair in the manner above described.

The above and other objects will become

apparent in the description below, in which characters of reference refer to like-named parts in the drawings.

Referring briefly to the drawings, Figure 1 represents a perspective view of my device opened and showing the hair wound upon the central rod therein.

Fig. 2 is a plan view of the same closed, the rod and hair being omitted.

Fig. 3 is a side view of the same.

Fig. 4 is an elevational view of a tube used in my device.

Fig. 5 is a view of said tube opened.

Fig. 6 is a cross-sectional view through said tube and the parts contained therein.

Fig. 7 is a view of the asbestos packing used in my device.

Fig. 8 is a view of the borax bag or packing used in my device.

Referring now in detail to the drawings, 75 the numeral 1 represents one half of a cylindrical tube, and 2 the other half thereof, the said halves being hinged together at 3. Each of said halves is provided with an inner jacket, 4 and 5, respectively, the front portions 7 and 8 respectively thereof being hingedly mounted upon the main portions of said jackets, by hinges 7^a and 8^a, respectively. Between said jackets and their outer wall members 1 and 2 are mounted fillers of 85 asbestos packing 6. The purpose of making the portions 7 and 8 hinged to the main body portions of the members 4 and 5, respectively, is to allow the removal and replacement of said asbestos packing; and the 90 purpose of the said packing is to provide a poor heat conductor which will retain most of the heat in the tube, below-mentioned, therein. Coils of heating wire 11 and 12 are passed, as shown, between the 95 inner tube walls and the asbestos, and are connected as shown into wires 13, both of which are then joined into the two-conductor wire 14, which is led to a suitable source of electrical energy, and a switch connected 100 in the usual manner.

Curved ears 10 are provided on the member 2, as shown, and spring-like ears 9 are provided on the other member, 1, adapted to snap over the members 10 and so releasably hold the tube in closed position.

I take a central rod 15, and grasping a handful of hair, comb it out and place the rod 15 at right angles to the said hairs and at the outer ends thereof; then I wind the 110

said hair on said rod in the manner of winding cloth upon a roll, the outer ends of the hairs being placed on the rod. When the rod has been wound so that the rod and its roll of hair are within about one-half inch of the head, I wind about the same a wrapper of borax bag 17, as shown in Figs. 8 and 6. This is simply a bag or packing containing borax and composed of ordinary linen 10 or any other desirable material. About this borax wrapper I then inclose a tube 18 of stiff paper or the like, being preferably composed of a single piece having a fold or hinge at the middle, as shown in Fig. 5. 15 The said borax wrapper and tube 18, when in position, leave an opening 21 through which the head-ends of the hairs 16 pass. The tube 18 is then closed at its end by, preferably, twisting the same and tying them 20 with cord 20. This tube, then, and its contents, is placed within the tube 1-2, said latter tube is then locked as described, and the same is then suspended horizontally over the head of the person by the wire 14; then 25 the electric current is turned on, heating the coils 11 and 12. This position is maintained for the usual length of time, whereupon the device is removed, and the hair presents a natural wavy appearance, having the advantages above described.

Having thus described my invention, what I claim and desire to secure by Letters Patent is as follows:

1. A permanent hair waver comprising an outer casing having two parts hinged together and adapted to be closed into the form of a tube, fixed ears on one of said parts and spring ears on the other adapted to mutually engage and releasably lock the device, an inner wall on each of said parts, asbestos packing between said inner walls and their respective casing walls, said inner walls being fixed at one end to said casing walls, the other ends thereof being bent out 40 ward and hingedly attached to the main body portions thereof, a central rod adapted to receive said hair, a borax wrapper adapt-

ed to inclose said hair and rod, and a flexible member adapted to inclose said wrapper, hair, and rod, the whole of said flexible 50 tube, wrapper, hair, and rod adapted to be placed within said casing with the ends of the hair passing out from said casing between the edges of the said parts of said casing.

2. A permanent hair waver comprising an outer casing having two parts hinged together and adapted to be closed into the form of a tube, fixed ears on one of said parts and spring ears on the other adapted 60 to mutually engage and releasably lock the device, an inner wall on each of said parts fixed at one end to said casing parts, asbestos packing between said inner walls and casing, the other ends thereof being bent 65 outward and hingedly attached to the body portion of said inner walls, and means adapted to be placed in said casing containing hair wound thereon, electric heat coils being mounted between said packing and 70 said inner walls.

3. A permanent hair waver comprising an outer casing having two parts hinged together and adapted to be closed into the form of a tube, fixed ears on one of said 75 parts and spring ears on the other, said ears adapted to mutually engage and releasably lock the device, an inner wall on each of said parts, asbestos packing between said inner walls and their respective casing 80 walls, said inner walls being fixed at one end to said casing walls and the inner ends thereof being bent outward against the casing walls, a central rod adapted to receive 85 hair wound thereon, a wrapper containing borax and adapted to inclose said hair and said rod, and a flexible member of stiff paper or the like adapted to inclose said wrapper, hair, and rod, the whole of said flexible tube, wrapper, hair, and rod being adapted 90 to be placed within said casing.

In testimony whereof I affix my signature.

WILLIAM SZLÁNYI.
